TRACK SANDING APPARATUS

Augustus Nation, Birmingham, Ala.

Application July 22, 1939, Serial No. 286,029

3 Claims. (Cl. 291—11)

My invention relates to track sanding apparatus and has for an object the provision of an apparatus of this kind which will serve to transfer sand from a sand box to the track to be sanded without becoming stopped up or otherwise getting out of order.

My invention further contemplates the provision of a sanding apparatus employing air for transferring the sand from the box to the tracks and in which the air is properly regulated as to pressure and so directed as to prevent the usual cutting of the several parts.

My invention embodies other novel features, details of construction and arrangement of parts which are hereinafter set forth in the specification and claims and illustrated in the accompanying drawing, forming part thereof, wherein:

Fig. 1 is a side elevational view showing my improved track sanding apparatus;

Fig. 2 is a sectional view taken along the line II—II of Fig. 1;

Fig. 3 is a sectional view taken along the line III—III of Fig. 1;

Fig. 4 is a sectional view taken along the line IV—IV of Fig. 1;

Fig. 5 is a sectional view taken along the line V—V of Fig. 2; and

Fig. 6 is a sectional view taken along the line VI—VI of Fig. 2.

Referring now to the drawing for a better understanding of my invention, I show a track sanding apparatus comprising a housing 7 having a sand passageway 8 which starts at the inlet opening 9 disposed within the sand box 11 and extends upwardly and outwardly and terminates in a downwardly disposed outlet opening 12 which is threaded to receive a conduit 13 leading to the track to be sanded. The housing is threaded to engage in the threaded opening 14 provided in the sand box.

A flanged opening 16 is provided in the housing 7 to receive a plug member 17 which is held in position by means of screws 18. The plug member is formed with an air chamber 19 having an air supply conduit 21 leading thereto. A primary air passageway 22 is formed in the plug member and is connected with the air chamber 19 by a converging passageway 23 which also serves as a valve seat for the adjustment screw 24. The primary air passageway 22 extends from the plug member through a pipe conduit 26 to a position adjacent the inlet opening 9. A cleanout plug 27 is provided to close one end of the passageway 22.

A secondary air passageway 28 is formed in

the plug member 17 and is connected with the air chamber 19 by a converging passageway 29 which also serves as a valve seat for the adjustment screw 31. One end of the passageway 28 is closed by means of a clean-out plug 32, and the other end of the passageway leads through a restricted orifice 33 to an air discharge chamber 34 disposed to direct a stream of air through the center of the outlet opening 12.

An auxiliary passageway 36 is provided in the plug member 17 to direct air from the air supply conduit 37 to the air discharge chamber 34.

In the operation of the apparatus described, the air passes through the conduit 21 to the air chamber 19 and thence through the passageways 23 and 29 to the passageways 22 and 28, respectively. The air passing through the primary passageway 22 is directed through the sand inlet opening 9 for the purpose of agitating and lifting the sand within the sand box upwardly through the sand inlet opening and into the sand passageway 8; while the air passing through the secondary passageway 28 is directed downwardly through the air discharge chamber 34 into the sand outlet conduit 13 and thus acts to draw the sand through the sand passageway from the inlet opening 9 to the outlet opening 12. The adjustment screws 24 and 31 may be regulated to vary the amount of air passing through the passageways 22 and 28, respectively. After the track has been sanded, air is admitted to the auxiliary passageway 36 to clean the sand out of the conduit 13 to prevent clogging of same.

While I have shown my invention in but one form it is obvious to those skilled in the art that it is not so limited but is susceptible of various changes and modifications without departing from the spirit thereof; and I desire, therefore, that only such limitations shall be placed thereupon as are imposed by the prior art.

I claim:

1. In a track sanding apparatus to be mounted on a sand box, a housing, a sand passageway extending through the housing and having an inlet opening and an outlet opening, said passageway extending upwardly and outwardly from the inlet opening to the outlet opening and thence downwardly through the outlet opening, said passageway having its inlet opening disposed within the sand box and facing downwardly, a primary air passageway provided within the housing and located to direct a stream of air from adjacent one side of the

inlet opening into the sand box to lift the sand upwardly and outwardly through the inlet opening and through the sand passageway, said passageway and its inlet opening being sufficiently large to receive the sand blown back therein, a secondary air passageway provided within the housing for directing a stream of air outwardly through the outlet opening of the sand passageway, an air chamber provided with an air inlet opening, and individual passageways leading from said air chamber to the pri-

mary air passageway and the secondary air passageway.

2. An apparatus according to claim 1 in which, the individual passageways serve as seats for adjustment screws for regulating the flow of air through the passageways.

3. An apparatus according to claim 1 in which, the several air passageways are formed in a plug which is detachably connected to the housing adjacent the outlet end thereof.

AUGUSTUS NATION.
